CHASING MILL WITH STATIONARY TABLE
AND RADIALLY ARRANGED ROLLER

William B. Chapman, Colorado Springs, Colo.

Application May 29, 1945, Serial No. 596,551

10 Claims. (Cl. 241—109)

1

My invention relates to grinding mills employing rollers which both roll and skid.

My object is to provide a mill of this character adaptable for processing ores, minerals, medicinals, paints, cements, herbs, plastic masses and their component parts. Other objects will appear as the description progresses.

Figure 1 represents a front view of a mill unit constructed in accordance with my invention; Fig. 2, a top view of Fig. 1; Fig. 3, an enlarged vertical cross section partly broken away; Fig. 4, a fragmentary top view of the rollers and guide structure; Fig. 5, a sectional view on the line 5—5 in Fig. 3; Fig. 6, a sectional view of the upper portion of the frame structure on the line 6—6 in Fig. 3; Fig. 7, a fragmentary view of the vertical shaft showing the peripheral groove; Fig. 8, a top view of a modification of the mill unit provided with facilities for angular adjustment of the roller shafts; Fig. 9, a front view of Fig. 8, partly broken away; Fig. 10, a fragmentary top view of the guide structure, jointed guide blocks, and rollers; Fig. 11, an enlarged fragmentary view showing the jointed guide block in a guide way; Fig. 12, a top view of a jointed guide block; Fig. 13, a side view of Fig. 12; Fig. 14, an enlarged sectional view of an outer end assembly; Fig. 15, a top view of a stud and shaft assembly; Fig. 16, a front view of Fig. 15; and Fig. 3A a fragmentary view of the spring and guide structure.

Although I show the preferred embodiments of my invention, I do not thereby limit myself to the precise forms shown but wish it understood that such forms come within the scope of what hereinafter is claimed, and that various changes in the precise details may be made within the scope of the claims without departing from the spirit of the invention.

The mill unit first illustrated in the drawings includes a frame structure, a vertical shaft, a guide structure, a feed tube, a series of horizontally disposed arms, a horizontal shaft under each horizontal arm, a roller on each horizontal shaft, and a grinding table.

The foundation of the frame structure comprises horizontal side bars 1—2, horizontal lateral end bars 3—4, and a middle lateral bar 5. One end consists of oblique bars 6—7 the lower ends of which are secured to the foundation by welding or otherwise and the upper end portions tied together by a tie bar 8. The other end consists of oblique bars 9—10 the upper end portions of which are connected by a tie bar 11 and the lower ends secured to the foundation by welding or otherwise. A longitudinal top bar 12 is secured

2

to oblique bars 6 and 9 at the top portions and a longitudinal top bar 13 is secured to the upper end portions of oblique 7 and 10. A bearing 14 is mounted on the middle lateral bar 5, and a ball bearing is mounted on the top of the longitudinal bars 12—13. This ball bearing consists of a lower ball race member 15, an upper ball race member 16 and balls 17.

The vertical shaft 18 is threaded at the upper 10 end portion and is mounted in bearing 14 and the ball bearing. A nut 19 is screwed on the vertical shaft 18 against the upper ball bearing race member 16 and a lock nut 20 is screwed in the nut 19.

The guide structure includes two horizontally 15 disposed annular plates 21—22, a series of vertically disposed flat plates 46, the ends of which are secured to the annular plates, and a spider member having a hub 23, and arms 34 which are secured to the interior of the guide structure.

20 The vertical plates are disposed in pairs, the members of each pair being spaced to provide guideways 25. The hub 23 of the spider member is mounted on the vertical shaft 18 and secured by set screws 26 extending into the peripheral groove 25 26A in the shaft 18.

The lower portion of the feed tube 27 is disposed in the guide structure and rests on the spider member arms 24. A spider member 65 is mounted on the vertical shaft 18 and supports 30 the upper portion of the feed tube. A funnel 66 is disposed on the upper end of the feed tube and secured by a collar 67.

The inner end portions of the horizontal arms 30 are mounted on the upper annular plate 22 35 and secured by welding or otherwise so as to extend outwardly from the guide structure. A lug 31 depends from the outer end portion of each horizontal arm and is provided with projections 32—33. A block 34 is disposed between the projections 32—33 on each lug 31 and a block 35 is disposed in each guideway 25 in the guide structure.

40 A horizontal shaft 36 is disposed beneath each arm 30 with one end extending through block 34 and the other end extending through block 35. A pin 37 runs through block 34, projection 32—33 and the end portion of shaft 36, thereby pivotally connecting shaft 36 to the depending lug 31. The hole in guide block 35 is larger than the shaft 36 and is disposed obliquely 45 so as to afford clearance for the shaft when the block moves upward in the guideway.

50 A roller assembly is mounted on each horizontal shaft 36. Each roller consists of an outer cylindrical shell R with a head mounted in each 55 end portion. One head consists of the member 38

having a central hole and a recess concentric with the central hole. A bushing 39 is disposed in the central hole and mounted on the shaft 36 so that the head portion of block 34 is disposed in the recess. The other head is integral with a stepped cone 40 which contains a bushing 41 mounted on the shaft 36.

A conical distributor 42 is mounted on the vertical shaft 18 below the feed tube 27 and secured by a collar 42 and set screw 43. A horizontally disposed circular grinding table 44 is mounted on the frame work foundation below the rollers and the conical distributor. A circular driving band 45 is mounted on the depending lugs 31 and is adapted to be operated by a belt 45B. Open springs 25A may be disposed in each guideway 25 to increase the pressure of the rollers.

The mill may be operated by a belt around the driving band or by any other suitable means.

Material is introduced through the funnel 66 and the feed tube 27 and strikes the conical distributor 42 which directs it towards and under the stepped cone portions 40 of the rollers. The stepped cone end of each roller is free to rise and fall as indicated by the dotted position in Fig. 3. This is facilitated by reason of the shaft 36 being mounted in guide block 35 in the guideway 25, and the pivotal connection of the shaft 36 in the lugs 31. This takes care of the coarse material as it is received in the various sizes at the inner ends of the rollers and yet holds the rollers in substantial uniform relation to the grinding table at the outer ends of the rollers so as to deliver the material relatively finer than when introduced. The material is discharged at the peripheral edge of the grinding table so that the material may be collected in any suitable manner. The springs 25A exert pressure on the guide blocks so as to increase the crushing effect of the rollers.

The whole movable assembly may be raised by screwing nuts 19-20 downward on the vertical shaft 18 thereby increasing the space between the rollers and the grinding table.

The modification shown in Figs. 8-9 has the same frame structure, guide structure, feed tube and grinding table as the unit illustrated in Figs. 1-2. This modification affords facilities and means whereby the rollers may be disposed at different relative angles to facilitate processing different materials. The angular dispositions increase or decrease the slippage or skidding of the rollers.

This modification includes a jointed guide block at the inner end of each roller and a stud assembly at the outer end. The jointed guide block consists of two parts 58-59 pivoted together by a pin 60. The part 58 slides in the guideway in the guide structure as in the mill unit first described.

In addition to the driving band 45 which is mounted on the horizontal arms 30, an auxiliary band 46 is spaced from the band 45 to provide a slot 48 and secured to the band 45 by cleats 47. A horizontally disposed stud 50 is provided with a threaded shank and a tongue T. The threaded shank extends through the slot 48 and is secured by nuts 51-52 screwed thereon against spacer collars which are wedge shaped. Spacer collars 53-54 are disposed between nut 52 and nut 51 and the bands, and spacer collars 55-56 are disposed between nut 52 and the bands. The inner end of each shaft 57 is disposed in the recess 61 of the jointed guide block and the outer end is provided with a slot S in which the

tongue T of the stud 50 is normally disposed. A thrust collar 62 is disposed on the slotted end of each shaft 57 adjacent to the shoulder of each threaded shank of a stud. A roller is mounted on each shaft 57 as in the mill unit first described.

The angular positions of the rollers may be altered to suit the requirements of various materials to be processed, in the following manner: 10 The nuts 51-52 are loosened and the shafts 57 swung on the pins 60 to the desired angular positions, the wedge spacer collars are turned to the proper relative positions to accommodate the new positions of the shafts 57, and the nuts tightened. As the rollers travel over the material being processed, the inner ends can rise and fall because of the vertical movement of the guide block as in the mill unit first described, said movement being facilitated by the tongue and slot assembly at the outer end of the shafts 53.

I claim:

1. A mill comprising a frame structure; a bearing mounted in the lower portion of said frame structure; a bearing mounted in the upper portion of said frame structure; a vertical shaft mounted in said bearings; a horizontally disposed guide structure provided with vertical guideways and mounted on said vertical shaft; a block provided with a bearing and disposed in each guideway so as to move vertically therein; a series of horizontally disposed arms mounted on said guide structure and extending outward therefrom; a vertically disposed lug depending from the outer end portion of each horizontal arm; a block pivotally mounted in each depending lug; a horizontally disposed shaft having one end connected to the last named block and the other end slidably disposed in the first named block; a roller rotatably mounted on each horizontal shaft; a horizontally disposed grinding table mounted in the lower portion of said frame structure below said rollers and adapted to cooperate therewith; and a horizontally disposed driving band mounted on the outer ends of said horizontally disposed arms.

2. A mill comprising a frame structure; a bearing mounted in the lower portion of said frame structure; a bearing mounted in the upper portion of said frame structure; a vertical shaft mounted in said bearings; a horizontally disposed guide structure provided with vertical guideways and mounted on said vertical shaft; a block provided with a bearing and disposed in each guideway so as to move vertically therein; a series of horizontally disposed arms mounted on said guide structure and extending outward therefrom; a vertically disposed lug depending from the outer end of each horizontal arm; a block pivotally mounted in each depending lug; a horizontally disposed shaft having one end connected to the last named block and the other end slidably disposed in the first named block; a roller rotatably mounted on each horizontal shaft; and a horizontally disposed grinding table mounted in said frame structure below said rollers and adapted to cooperate therewith.

3. A mill comprising a frame structure; a bearing mounted in the lower portion of said frame structure; a bearing mounted in the upper portion of said frame structure; a vertically disposed shaft mounted in said bearings; a horizontally disposed guide structure provided with vertical guideways and mounted on said vertical shaft; a series of horizontally disposed arms mounted on said guide structure and extending

outward therefrom; a vertically disposed lug depending from the end portion of each horizontal arm; a horizontally disposed shaft disposed below each horizontal arm, one end of said shaft being pivotally connected to a depending lug and the other end slidably disposed in a guideway of the guide structure; a roller rotatably mounted on each horizontal shaft; and a grinding table mounted in said frame structure below said roller and adapted to cooperate therewith.

4. A mill comprising a frame structure; a bearing mounted in the lower portion of said frame structure; a bearing mounted in the upper portion of said frame structure; a vertically disposed shaft mounted in said bearings; a horizontally disposed guide structure provided with vertical guideways and mounted on said vertical shaft; a series of horizontally disposed arms mounted on said guide structure and extending outward therefrom; a lug depending from the outer end portion of each horizontal arm; a horizontally disposed shaft disposed below each horizontal arm, one of said shafts being pivotally connected to a depending lug and the other end slidably disposed in a guideway in said guide structure; a roller rotatably mounted on each horizontal shaft; a stepped cone member integral with the inner end of each roller; and a grinding table mounted below said rollers and adapted to cooperate therewith.

5. A mill comprising a frame structure; a bearing mounted in the lower portion of said frame structure; a bearing mounted in the upper portion of said frame structure; a vertically disposed shaft mounted in said bearings; a guide structure provided with vertical guideways and mounted on said vertical shaft; a block provided with a bearing and slidably disposed in each guideway; a series of horizontally disposed arms mounted on said guide structure and extending outward therefrom; a lug depending from the outer end portion of each lug; a block pivoted in each lug; a horizontally disposed shaft under each horizontal arm, one end of said shaft being connected to the last named block and the other end slidably disposed in the first named block; a roller rotatably mounted on each horizontal shaft; a stepped cone member integral with the inner end of each roller; and a grinding table mounted below said rollers and adapted to cooperate therewith.

6. A mill comprising a frame structure; a bearing mounted in the lower portion of said frame structure; a bearing mounted in the upper portion of said frame structure; a vertically disposed shaft mounted in said bearings; a guide structure provided with vertical guideways and mounted on said vertical shaft; a series of horizontally disposed arms mounted on said guide structure and extending outwardly therefrom; a lug depending from the outer end of each horizontal arm; a horizontally disposed shaft under each horizontal arm, one of said horizontal shaft being pivotally connected to a depending lug and the other end slidably disposed in a guideway in the guide structure; a roller rotatably mounted on each horizontal shaft; a stepped cone member integral with each roller at the inner end; a feed tube mounted in said guide structure; a conical distributor member mounted on said vertical shaft below said feed tube; and a grinding table mounted below said rollers and adapted to cooperate therewith.

7. A mill comprising a frame structure; a bearing mounted in the lower portion of said frame

structure; a bearing mounted in the upper portion of said frame structure; a vertical shaft mounted in said bearings; a horizontally disposed guide structure provided with vertical guideways and mounted on said vertical shaft; a series of horizontally disposed arms mounted on said guide structure and extending outward therefrom; a lug depending from the outer end of each horizontal arm; a horizontally disposed shaft, one end of which is pivotally connected to a depending lug and the other end disposed in a guideway of said guide structure and adapted to move vertically therein, there being a horizontally disposed shaft for each horizontally disposed arm; a roller rotatably mounted on each horizontally disposed shaft; a horizontally disposed grinding table mounted in said frame structure below said roller and adapted to cooperate therewith; a vertically disposed feed tube, the lower portion of which is disposed in said guide structure; a horizontally disposed driving band mounted on the horizontally disposed arms; a conical distributing member mounted on said vertical shaft below said feed tube; a vertical adjusting means for said vertical shaft; and a stepped cone mounted on each horizontal shaft.

8. A mill comprising a frame structure; a bearing mounted in the lower portion and a bearing mounted in the upper portion of said frame structure; a vertical shaft mounted in said bearings; a horizontally disposed guide structure provided with vertically disposed guideways and mounted on said vertical shaft; a block provided with a bearing and slidably disposed in each guideway; a series of horizontally disposed arms mounted on said guide structure and extending outward therefrom; a lug depending from the outer end of each horizontal arm; a block pivotally mounted in each depending lug; a horizontally disposed shaft, one end of which is disposed in the last named block and pivotally connected thereto; and the other end slidably mounted in the first named block; a roller provided with a stepped cone portion and mounted on said horizontal shaft, there being a horizontal shaft under each horizontal arm; a feed tube, the lower portion of which is disposed in said guide structure; a distributing member mounted on said vertical shaft below said feed tube; a driving band mounted on the outer ends of said horizontal arms; means to adjust said vertical shaft longitudinally mounted on said upper bearing; and a circular grinding table mounted in said frame structure below said rollers.

9. A mill comprising a frame structure; a bearing mounted in the lower portion of said frame structure; a bearing mounted in the upper portion of said frame structure; a vertical shaft mounted in said bearings; a horizontally disposed guide structure provided with vertical guide ways and mounted on said vertical shaft; a plurality of horizontally disposed arms mounted on said guide structure and extending outward therefrom; a plurality of jointed guide blocks, one member of each guide block being slidably disposed in a vertical guide way; a driving band mounted on the outer ends of said horizontal arms; an auxiliary band spaced from said driving band and secured thereto by suitable means; a vertically disposed feed tube mounted in said guide structure; horizontally disposed shafts, each shaft being provided with a slot in its outer end portion and the inner end portion disposed in a member of a jointed guide block; a roller mounted on each horizontal shaft; a series of

studs, each stud being provided with a threaded shank and a tongue, the tongue being disposed in the slot in the end portion of the adjacent horizontal shaft and the shank extending through the slot between said bands; a nut screwed on each shank on the inner side of said bands and a nut screwed on each shank on the outside of said bands; and a grinding table mounted in said frame structure below said rollers.

10. A mill comprising a frame structure; a bearing mounted in the lower portion and a bearing mounted in the upper portion of said frame structure; a vertical shaft mounted in said bearings; a horizontally disposed guide structure provided with vertical guide ways and mounted on said shaft; a plurality of horizontally disposed arms mounted on said guide structure and extending outward therefrom; a plurality of jointed guide blocks, one member of each guide block being disposed in a guideway in said guide structure; a driving band mounted on the outer ends of said horizontal arms; an auxiliary band spaced from said driving band to provide a slot and secured to the driving band by suitable means; a vertically disposed feed tube mounted in said guide structure; horizontally disposed shafts, each shaft being provided with a slot in its outer end and the inner end disposed in a member of a jointed guide block; a roller mounted on each horizontally disposed shaft; a grinding table 30

mounted in said frame structure below said rollers; a series of studs, each stud being provided with a threaded shank and a tongue, the tongue being disposed in the slot in the adjacent horizontal shaft and the shank extending through the slot between said bands; a nut screwed on each shank on the inside of said bands and a nut screwed on each shank on the outside of said bands; a pair of wedge spacer collars disposed on each shank between the nut on the inside of said band and the bands, and a pair of wedge spacer collars disposed on each shank between the nut on the outside of said bands and the bands; and a thrust collar on the outer end of each horizontal shaft adjacent to the shoulders of the shank of each stud.
